(57) CLAIM

The ornamental design for the rolled roofing material, as shown and described.

DESCRIPTION

FIG. 1 is a perspective view of decorative roof with the peaks lined up from row to row;

FIG. 2 is a top plan view of the decorative roof design of FIG. 1;

FIG. 3 is a fragmented enlarged view of the rolled roofing material showing a portion of the claimed design that has been cut out of a roll of roofing material. The broken lines are for illustrative purposes only and form no part of the claimed design.

FIG. 4 is a perspective view of a second embodiment of a rolled roofing material with the peaks lined up with the mid peak from row to row;

FIG. 5 is a top plan view of the decorative roof design of FIG. 4;

FIG. 6 is a perspective view of a third embodiment of a rolled roofing material with the peaks lined randomly from row to row; and,

FIG. 7 is a top plan view of the decorative roof design of FIG. 6.

The ends of the claimed design are broken away to indicate indeterminate length.
